P. C. BEAN & H. S. COLLINSON.
SIDE CURTAIN FOR AUTOMOBILES.
APPLICATION FILED NOV. 25, 1913.

1,145,965.

Patented July 13, 1915.

UNITED STATES PATENT OFFICE.

PRESTON C. BEAN AND HARRY S. COLLINSON, OF ARKANSAS CITY, KANSAS.

SIDE CURTAIN FOR AUTOMOBILES.

1,145,965.

Specification of Letters Patent. Patented July 13, 1915.

Application filed November 25, 1913. Serial No. 802,970.

To all whom it may concern:

Be it known that we, PRESTON C. BEAN and HARRY S. COLLINSON, citizens of the United States, residing at Arkansas City, in the county of Cowley, State of Kansas, have invented certain new and useful Improvements in Side Curtains for Automobiles; and we do hereby declare the following to be a full, clear, and exact description of the invention, such as will enable others skilled in the art to which it appertains to make and use the same.

The present invention is directed to improvements in side curtains for automobiles, and has for its object to so construct a curtain of this type adapted when in use to occupy a space between the rear of the top and front top brace, or wind shield.

A further object of the invention is to provide a device of this character which may be easily and quickly applied to an automobile top of the conventional form, and is so constructed that the same may be operated to fold with the top when not in use.

With these and other objects in view, this invention resides in the novel features of construction, formation, combination and arrangement of parts to be hereinafter more fully described, claimed and illustrated in the accompanying drawing, in which:—

Figure 1 is a fragmentary side elevation of an automobile, showing the device in place. Fig. 2 is a similar view showing the top of the automobile folded, the position of the device being indicated in dotted lines. Fig. 3 is a side elevation of an automobile, showing the curtain in its operative position. Fig. 4 is a sectional view on line 4—4 of Fig. 1. Fig. 5 is a similar view on line 5—5 of Fig. 1. Fig. 6 is a similar view on line 6—6 of Fig. 1.

Referring to the drawing, the numeral 1 designates a cylindrical casing formed from light sheet metal, and has its forward side provided with a longitudinal slot 2 in which is revolubly mounted rollers 3, the purpose of which will appear later.

The upper and lower ends of the casing are closed, the upper end being provided with an ear 4 which is pivotally connected by a bolt 5 adjacent the upper end of the inclined bow 6 forming one of the braces for the usual top 7.

Mounted within the casing 1 is a spring roller 8, and adapted to wind and unwind thereupon is a curtain 9, said curtain being

formed from suitable fabric and is provided with slits 10 and 11, which are so arranged that persons may easily enter or leave the vehicle by the rear or fore-door of the machine.

Pivottally connecting the casing 1 and bow 6 are brace bars 12, the opposing ends of which are connected by a joint 13, which is adapted to break upwardly so that the casing can be swung forwardly when it is desired to fold the top, said brace bars also serving to hold the casing 1 against swinging forward when the curtain 9 is being unwound from the roller 8.

The lower side edges of the cover 7 are provided with spring actuated clasps 14, which are adapted to detachably engage the upper edge of the curtain 9 to prevent wind or rain from entering the top above the curtain, as clearly shown in Fig. 6 of the drawing.

The lower end of the casing 1 is provided with a plate 15 which is adapted to rest upon the usual bow support 16 when the casing is in the position as shown in Figs. 1 and 3. Thus it will be seen that the casing will prevent accidental folding of the top when the front bows 17 are disengaged previous to the complete folding of the top.

The curtain 9 has its normally forward edge provided with a metallic strip 18, the upper and lower ends of which are provided with hooks 19, said hooks being adapted to engage the bow 17 or side edges of the wind shield, thereby holding the curtain in its operative position.

When it is desired to fold the vehicle top it is only necessary to break the joint 13 of the brace bars 12 upwardly, and to swing the casing 1 forwardly, whereupon the top may be folded in the usual manner, and will occupy a position as shown in dotted lines in Fig. 2 of the drawing.

By providing the rollers 3 it is obvious that the curtain 9 can be wound or unwound without injury when passing through the slot, and that undue friction will be eliminated.

The strip 18 is provided with a handle 21, which is grasped for unwinding the curtain so that the hooks 19 may be engaged with the bow 17 or wind shield 20.

What is claimed is:

The combination with a vehicle having a top and rest therefor, an elongated casing pivotally secured to the upper portion of the

top thereof, means on the lower end of the casing constructed and arranged to detachably engage the top rest, a curtain revolubly mounted in the said casing and adapted to be drawn therefrom, a folding brace member pivotally secured to the casing and to one side bar of the top whereby the casing will be held in a vertical position, the said casing being constructed and arranged so as 10 to lie horizontally upon the rest upon the

folding of the said brace member and the top.

In testimony whereof, we affix our signatures in the presence of two witnesses.

PRESTON C. BEAN.
HARRY S. COLLINSON.
